UNITED STATES PATENT OFFICE.

CARLOS KOBAU, OF CAMPANA, ARGENTINA.

APPARATUS FOR AUTOMATICALLY CHARGING CONTAINERS WITH PREDETERMINED AND ADJUSTABLE AMOUNTS OF LIQUIDS OR THE LIKE.

Application filed August 16, 1926, Serial No. 129,596, and in Argentina March 18, 1926.

This invention relates to an improved automatic apparatus for charging containers with liquids and the like; and its object, broadly speaking, is to provide an automatically operating device of simple construction which allows of charging containers with liquids or similar fluids in predetermined amounts, which can be controlled at will, the operation of the apparatus taking place in a continuous manner.

The invention has other objects also which will be clearly described in the course of this specification and will be claimed hereinafter.

In order that the invention may be readily understood and carried into practice, a preferred embodiment of the same has been illustrated in the accompanying drawings, wherein:—

Figure 1 is a plan view, partially sectional and with parts broken away or omitted, of the complete apparatus.

Fig. 2 is a central longitudinal section on line 2—2, Fig. 1.

Figs. 3, 4 and 5 are cross-sections taken, respectively, on lines 3—3, 4—4, and 5—5 of Fig. 2; and

Fig. 6 is a cross-section taken substantially on the line 6—6 of Fig. 2.

According to the form of construction shown, the apparatus consists of a controller compartment 1, in the interior of which is mounted, in suitable bearings 2 and 3, a controller in the form of a hollow cylindrical body 5 having rounded ends and adapted to tilt or oscillate on its axle 4. This body or container 5 is provided on its upper side with a lid or cover 6 which closes an inlet for the admission of a liquid or fluid, such as oil, for instance, and a heavy ball 7 is adapted to roll freely in the interior of said body, the oil contained therein serving to damp its impacts against the ends of the same. Below the body 5 is securely supported a rail or track 8, along which runs a roller 9; the ends of the rail being curved upward and having their upper portions 8' bent slightly inward so that the roller will tend to stay within either of them, whereby the body 5 will be caused to occupy normally one or the other of its inclined positions, as shown in

Fig. 3. The rail 8 is provided at opposite ends with stops 10 against which a pair of arms 11 suspended from said roller and carrying at their lower ends a roller 12 is adapted to abut; said roller 12 being at-

ranged to travel on a jointed bar 12', the two members of which are provided with stops 13 and pivoted at their outer ends 14 to the end walls of the compartment 1, while their slotted inner ends have a lost-motion pivotal mounting on a pin 15 attached to the top of a hollow float 16 which substantially fills the lower part of the interior of the compartment. The float 16 rises or descends as the liquid enters into or issues from the float chamber 16' (Fig. 3) beneath the same.

This chamber 16' is equipped with two gate valves 17 and 18 (Fig. 4) which alternately open and close by the operation of a pair of arms 19 and 20 connected to links 21 and 22 which, in turn, are connected by means of links 23 and 24 to the ends of a walking beam 25, the axle of which constitutes an extension of the axle 4 of the tilting body 5, so that the movements of said body and axle will be transmitted to the said valves so as to alternately open and close the same. These valves 17 and 18 control communication between the float chamber or compartment 16' and two compartments 26 and 27 which serve as discharge reservoirs and which are provided at their bottoms with outlet spouts 28 and 29 (Fig. 6). The spouts are alternately opened and closed by means of valves 30 and 31 provided with depending fingers 32 suitably guided in gratings 33; and on the lower end of each spout is fitted a nut 34 constructed in such a way as to avoid the formation of whirls in the outflowing liquid. The stems 35 and 36 of valves 30 and 31 are provided with collars 37, to which are pivoted forks 38 and 39 secured to horizontally-arranged, longitudinal shafts 40 and 41 (Fig. 1) to which motion is imparted by the previously-mentioned links 21 and 22 connected to the gate valve arms 19 and 20. By means of this arrangement, a synchronous operation of the two pairs of valves is obtained.

42 and 43 (Fig. 4) are pipes which lead from the tops of the discharging compartments 26 and 27 to the upper part of the charging reservoir 55, to enable the air to escape from said compartments, the links 23 and 24 passing through these pipes.

The said discharging compartments 26 and 27 communicate with the regulating compartments 44 and 45 (Fig. 1) which are arranged at the ends thereof, by means of the siphons 46 and 47. The siphons terminate

in tubes 48 disposed in the regulating compartments 44 and 45, each tube being fitted at its upper end with a gland 49'; and within each tube slides another tube 49 (Fig. 2), the upper open end of which is connected to the lower face of a funnel or hopper 50 which extends substantially over the entire area of the regulating compartments and has an opening in register with the tube end. Each funnel 50 has connected to it a vertical rod 51 carrying a vertical rack 52, that meshes with and is operated by a pinion 53 provided with a crank or other suitable device (not shown) for rotating it. The rack 52 is located immediately adjacent to and works in conjunction with an indicating scale 54.

The regulating compartments 44 and 45 being in communication with the discharging compartments 26 and 27 through the siphons 45 and pipes 48 and 49, it will be apparent that if the level of the liquid in either regulating compartment is above the hopper 50 therein, such liquid will pass into the corresponding discharging compartment through the connections specified when the discharging compartment is being emptied; but no liquid below the hopper will flow out. Consequently, by lowering the hopper by means of the pinion 53 and connected parts, the quantity of liquid transferred from the regulating compartment to the discharging compartment may be controlled at will.

35 Above the discharging compartments 26 and 27 is arranged the main charging reservoir 55, provided with an inlet 56 having a valve 57 which is operated through suitable links 58 by a float 59 disposed within said reservoir or compartment. In the bottom of the reservoir are provided two ports 60 and 61 (Fig. 5) in communication with the discharging compartments 26 and 27, respectively, and which open into pipes 62 and 63 that extend nearly to the bottom of said compartments in order to avoid foaming, as will be readily understood. Said ports 60 and 61 are closed by valves 64 and 65 guided in cages 66 and 67 and adapted to be operated by a walking beam 68 pivoted at 69 and provided with a lug or projection 70 in engagement with a fork 71 which is rigidly secured to the main axle 4.

The arrangement of the valves 64, 65 is such that while the outlet valve 30 or 31 of a discharging compartment is closed, its inlet valve 64 or 65 will be open, and vice versa. Similarly, when the inlet valve is open, the gate or regulating valve 17 or 18 leading to the float chamber 16' beneath the float 16 in compartment 1 will also be open. As the movements will take place in alternation with regard to each side of the apparatus, the operation of the machine may be considered as being entirely continuous.

The changes of position of the valves will be effected by the alternate tilting movements of the body 5, due to the successive admissions of fluid or liquid to the float chamber 16' within the controller compartment 1, as will be clearly understood.

In order to determine at any desired moment the amount of liquid or fluid contained within the discharging compartments 26 and 27, there are provided indicators 72 and 73 (Fig. 4), in front of which are mounted glass tubes 74 and 75, each containing a slideable plunger 76' or 77' that is rigidly connected to a rod 76 or 77 provided at its lower end with a float 78 or 79 suitably guided in the interior of each of said compartments.

The operation is substantially as follows:—Starting with the inlet valve 57 of the main reservoir 55 open, liquid will flow through inlet 56 and fill said reservoir until the level has risen far enough to cause float 59 to close the valve. Assuming that valve 64, which controls port 60 and pipe 62 leading into discharging compartment 26 is open, and that gate valve 17 controlling the entrance of the fluid into float chamber 16' is likewise open, then liquid from reservoir 55 will pass into said discharging compartment and also into said float chamber with the result that the compartment is filled and the float 16 is raised; it being understood, of course, that the corresponding discharge valve 30 is closed. At the same time, liquid also flows through siphon 46 and pipes 48 and 49 into the corresponding regulating compartment 44 and fills the same; the hopper 50 having previously been adjusted by means of pinion 53 to the proper height for the particular quantity of liquid to be discharged, which can readily be determined by the position of rack 52 relative to scale 54 (Fig. 2).

The filling of float chamber 16' raises float 16, as just stated; and as the float rises, it pushes up the adjacent end of the hollow body 5, through the intermediary of the jointed bar 12', rollers 12 and 9, and arms 11. Said body 5 is thus tilted about its axis 4; and when said movement has progressed sufficiently far to enable ball 7 to travel to the other end of the hollow body, the tilting is completed, and the body will be maintained in its new position by the retention of the roller 9 in the curved portion at the then lower end of rail 8. The tilting movement of the hollow body is transmitted through its axle 4 to the two walking-beams 25 and 68, so that valves 64 and 17 are now closed and the discharge valve 30 is opened. Valves 65 and 18 are also opened and valve 31 is closed, in proper timed relation to the first-named valves, the two systems acting in alternation, as will be understood; but since the operations are the same in both

cases, a description of one cycle of movements will suffice.

With the closing of valve 64 and opening of valve 30, the flow into compartment 26 is cut off and discharge commences. The entire contents of said compartment will escape through outlet 28, and in addition all liquid in regulating compartment 44 above the level of hopper 50 therein will flow out 10 through pipes 49 and 48 and siphon 46 into compartment 26 to be discharged with the liquid therefrom. The liquid in the float chamber 16' will escape through the opening controlled by valve 18 into compartment 27, 15 the discharge valve 31 of which is closed at that time, as has been stated, so that float 16 falls and is ready for a fresh actuation.

I claim as my invention:

1. Apparatus for delivering predetermined amounts of liquid, comprising, a pair of discharging compartments each having an inlet valve and an outlet valve; a charging compartment in controlled communication with the discharging compartments by way 20 of their inlet valves; a controller compartment, a rising and falling float therein, and a float chamber beneath the float in communication with both discharging compartments; a pair of alternately-acting valves for controlling such communication; a controller in the controller compartment tiltable in opposite directions by the movements of the float; and valve-operating mechanism actuated by the tilting movements of the controller for automatically opening the inlet and float chamber valves of one discharging compartment and closing the outlet valve 25 thereof, and simultaneously closing the inlet and float chamber valves and opening the outlet valve of the other discharging compartment.

2. Apparatus for delivering predetermined amounts of liquid, comprising, a pair of discharging compartments each having an inlet valve and an outlet valve; a charging reservoir in controlled communication with the discharging compartments by way of their inlet valves, said reservoir having a liquid inlet; a valve in said reservoir for opening and closing said inlet; a float in the reservoir for operating said reservoir valve in accordance with variations in the liquid level; a controller compartment, a rising and falling float therein, and a float chamber beneath the float in communication with both discharging compartments; a pair of alternately-acting valves for controlling such communication; a controller in the controller compartment tiltable in opposite directions by the movements of the float; and valve-operating mechanism actuated by the tilting movements of the controller for automatically opening the inlet and float chamber valves of one discharging compartment 50 and closing the outlet valve thereof, and

simultaneously closing the inlet and float chamber valves and opening the outlet valve of the other discharging compartment.

3. Apparatus according to claim 1, in which the controller comprises a hollow body 70 mounted to rock about its transverse axis and connected with the float, and a weight movable in said body from one end to the other to govern its tilting movements, a track attached to the under side of said body, a roller movable from end to end of the track, and connections between said roller and the float to initiate the movements of the tilting body.

4. Apparatus for delivering predetermined amounts of liquid, comprising, a pair of discharging compartments each having an inlet valve and an outlet valve; a charging compartment in controlled communication with the discharging compartments by 80 way of their inlet valves; a controller compartment, a rising and falling float therein, and a float chamber beneath the float in communication with both discharging compartments; a pair of alternately-acting valves for 85 controlling such communication; a controller in the controller compartment tiltable in opposite directions by the movements of the float; a pair of walking beams, one connected with the two inlet valves and the other with the two float chamber valves for 90 opening the inlet and float chamber valves of one discharging compartment and simultaneously closing those of the other discharging compartment, both walking beams being connected to the controller to be operated in unison by the tilting movements thereof; and means operated simultaneously with said walking beams for opening and closing the outlet valves of the two discharging compartments in reverse relation to their inlet and float chamber valves.

5. Apparatus according to claim 4, in which the two outlet valves are actuated by devices operatively related to one of the 100 walking beams.

6. In an apparatus for delivering predetermined amounts of liquid, a discharging compartment; means for supplying liquid thereto; a valve-controlled outlet for said compartment; operating means for said valve; a regulating compartment; a siphon tube leading from the bottom of the discharging compartment through the bottom of the regulating compartment, and extending 115 upwardly in the latter compartment; a movable funnel in the regulating compartment having an open tubular stem which slidably fits in the extension of the siphon to enable liquid in said regulating compartment above the level of the funnel to pass 120 into the discharging compartment by way of the siphon; and means for adjusting the position of said funnel vertically.

CARLOS KOBAU.
